UNITED STATES PATENT OFFICE.

JOHN GEMEINHARDT, OF LITTLE FALLS, NEW JERSEY.

CIGARETTE CASE AND LIGHTER.

Application filed December 1, 1922. Serial No. 604,362.

To all whom it may concern:

Be it known that I, JOHN GEMEINHARDT, a citizen of the United States, residing at Little Falls, in the county of Passaic and State of New Jersey, have invented certain new and useful Improvements in Cigarette Cases and Lighters, of which the following is a specification, reference being had therein to the accompanying drawings.

10 This invention relates to a cigarette case and lighter device, and the object of the invention is the construction of a simple and efficient cigarette case which is provided with means for holding cigarettes, 15 and discharging same, one at a time, and at the same time of discharging the cigarette may be quickly lighted.

With the foregoing and other objects in view, my invention comprises certain novel 20 combinations, constructions and arrangements of parts as will be hereinafter described, illustrated in the accompanying drawings, and more particularly pointed out in the appended claims.

25 In the drawings:

Figure 1 is a view, in elevation, of a device constructed in accordance with the present invention.

Figure 2 is a top plan view of the device.

30 Figure 3 is a sectional view, taken on line 3—3, Fig. 2, and looking in the direction of the arrows.

Figure 4 is a sectional view, taken on line 4—4, Fig. 3, and looking in the direction 35 of the arrows.

Figure 5 is a sectional view, taken on line 5—5, Fig. 3, and looking in the direction of the arrows.

Figure 6 is an enlarged, fragmentary, vertical, sectional view of the device.

Figure 7 is a perspective view of one of the cigarette containers.

Figure 8 is an enlarged, sectional view, taken on line 8—8, Fig. 7, and looking in 45 the direction of the arrows.

Figure 9 is a sectional view taken on line 9—9, Fig. 6, showing how the contact arms are insulated from the outer casing.

Referring to the drawings by numerals, 50 1 designates the main or outer casing, and 2 designates the auxiliary or inner casing. The inner casing preferably extends through the top 3 of the outer casing 1, as clearly shown in Figs. 1, 2 and 6. In the extended 55 portion of the inner casing is a flashlight 4, of any ordinary construction. Within the

inner casing 2 is a battery 5 which is suitably connected to the flashlight 4 for causing the same to be illuminated at the will of the operator.

60 The bottom 6, of the outer casing 1, is hinged, at 7 Fig. 1, to the casing 1. The hinged bottom 6 allows the battery 5 to be placed in the inner casing, and the cigarette containers 8 to be placed between the inner 65 and outer casings, as shown in Figs. 3 and 4.

Each container 8 is tubular-shaped, and is open both at its top and bottom. The bottom of the container 8 is bevelled at 9, and this bevelled edge terminates in an inverted, V-shaped slot 10. Inwardly-extending lips 11 are formed upon the lower end of the container 8 for holding the cigarette up a slight distance above the hinged bottom 6, so that the lower end 12, of the lifter 70 device 13, will readily be positioned under the lower end of the cigarette to be lifted out of the container 8.

75 Each container 8 is provided upon its side with a pair of flanges 14 and with a lug 15. Each container is also provided with a grip 16. The containers are "linked" together with an endless chain (Fig. 4) by having a lug 15 of each container fit between the flange 14 of the next contiguous container. The operator can place his finger in the opening 17, causing the finger-nail to engage the grip 16, pushing the container, or containers, around the inner casing so that, successively, the containers are placed 80 parallel with an outwardly-bulged portion 18, in which the lifter device 13 is mounted.

As each container 8 reached its parallel position with portion 18, the lower end 12, of the lifter device 13, comes under the 85

cigarette in the container 8, and by the operator lifting on the knob 19, the cigarette can be lifted to the position shown by dotted lines 20, Fig. 6, whereupon the operator can grip, by hand or mouth, the cigarette 90

and draw it entirely out of the container and casing, and with the lifting of the lifter device 13, the upper end of said device will come in contact with both of the ends 21^a of the contact arms 21, closing the circuit 95

across these ends, and by reason of the ends 21^a and arms 21 (Fig. 5) being made of suitable metal to cause a high resistance, they will be heated red hot, whereby, by moving the hinged cover 22, Fig. 2, out of the way, 100

the cigarette can be lighted by pressing an end against the heated ends of the arms 21.

The arms 21 are suitably insulated from the top 3 of the outer casing, as shown in Fig. 9. The arms 21 are in contact with the battery 5, so that when the lifter device closes the 5 circuit between the ends 21^a of said arms, the heating of the ends to an incandescent degree, or red hot, will be accomplished for affording a ready lighter from the cigarette, that is extracted, or has been extracted from 10 the casing.

To fill the containers 8 all that is necessary is to open the bottom of the device and place the cigarettes in the containers and then close the hinged bottom 6.

15 It is to be noted that the end 12, of the lifter device 13, will readily ride up the bevelled edges 9, thence into the inverted, V-shaped slot 10, for readily lifting the cigarette, upon the operator raising the 20 knob 19.

While I have described the preferred embodiment of my invention, and have illustrated the same in the accompanying drawings, certain minor changes or alterations 25 may appear to one skilled in the art to which this invention relates, during the extensive manufacture of the same and I, therefore, reserve the right to make such alterations or changes as shall fairly fall 30 within the scope of the appended claims.

What I claim is:

1. In a device of the class described, the combination of an inner and an outer casing, said outer casing provided with an 35 opening, a plurality of containers between said casings, each container provided at one side with a pair of parallel flanges and upon its other side with a lug, the lugs of the containers fitting between the parallel 40 flanges, each container provided with a grip, said grip adapted to be positioned contiguous to said opening in the outer casing for permitting an operator to propel the containers around the inner casing; and means 45 for lifting cigarettes out of the casing from the containers.

2. In a device of the class described, the combination with a casing, of a container

within said casing, arms contiguous to said container, means connecting a source of 50 electricity to said arms, a lifting device co-operating with the container and also with said arms, whereby, when the lifting device is moved relative to the container the same will close a circuit across said arms, 55 whereby portions of the arms are heated for permitting a cigarette to be lighted.

3. In a device of the class described, the combination of a casing provided with a bulged portion, a container carried by said casing and adapted to register with said bulged portion, a lifter device slidably mounted upon the bulged portion, said lifter device provided with a knob extending through the bulged portion, said lifter device provided with a lower end extending into the container, contact arms carried by the casing and having their outer ends contiguous to the container, said lifter device adapted to engage the outer ends of 70 the contact arms and close a circuit therebetween, and means for supplying electricity to said arms.

4. In a device of the class described, the combination with an inner and outer casing, 75 said outer casing provided with a finger opening, a plurality of containers between said inner and outer casings and adapted to pass by said finger opening, means on each container for allowing the finger of the operator to propel the containers, and means for ejecting a cigarette from each of said containers.

5. In a device of the class described, the combination of a casing, a container within 85 said casing, said container provided with a lower, bevelled end and with supporting lips or flanges on said end and with an inverted V-shaped slot contiguous to said end, and a lifting device extending into said end and adapted to enter said V-shaped slot 90 for lifting a cigarette within said container.

In testimony whereof I hereunto affix my signature.

JOHN GEMEINHARDT.
